UNITED STATES PATENT OFFICE.

CHARLES W. CROGAN, OF BANGOR, MAINE.

DRUM-HANDLE FOR TAPE-LINE REELS.

1,375,630.

Specification of Letters Patent. Patented Apr. 19, 1921.

Application filed July 10, 1919, Serial No. 309,946. Renewed March 1, 1921. Serial No. 443,866.

To all whom it may concern:

Be it known that I, CHARLES W. CROGAN, a citizen of the United States, residing at Bangor, in the county of Penobscot and 5 State of Maine, have invented certain new and useful Improvements in Drum-Handles for Tape-Line Reels, of which the following is a specification.

This invention has for its object to provide an improved foldable handle for the winding drums of tape line reels in which the handle is automatically sprung to operative position by slight pressure exerted upon a conveniently accessible button located in the drum at a point adjacent the handle.

Another object is the provision of an automatic projecting device for the handle of a tape reel drum which is so constructed 20 as to afford means for releasably retaining the handle in folded or inoperative position.

With these and other objects in view as will appear as the description proceeds the invention comprises the novel features of 25 construction, accompanied by elements and arrangement of parts which will be more fully described in the following specification and set forth with particularity in the claims appended hereto.

30 Figure 1 represents a side elevation of a well known type of tape line reel illustrating the invention applied to use,

Fig. 2 represents a fragmentary perspective view of the interior of the winding 35 drum, removed from the casing illustrating the controlling device for the handle in detail,

Fig. 3 represents a fragmentary sectional view through the drum in the plane of the 40 longitudinal axis of the handle, and,

Fig. 4 represents a diametrical sectional view through the drum in the plane of the longitudinal axis of the retaining spring for the handle.

45 Referring to the drawing in detail, wherein similar reference characters designate corresponding parts throughout the several views, the numeral 5 indicates a conventional type of tape line reel casing and although a particular shape of casing has been illustrated in the accompanying drawing it is to be understood that I am not limited in any respect to the type of casing to which the invention is applicable. As usual, the 55 casing 5 constitutes a housing for the flexi-

ble tape line (not shown) the terminal of which is fastened to a circular drum 6 rotatably mounted adjacent the center of the casing 5 and provided with an annular flange 7 engaging the outer surface of one 60 side wall of the casing to maintain the drum in proper relation thereto during rotary movement of the drum.

Apertured ears 8 are secured to or formed integral with the side wall of the drum 6 65 and receive a pivot pin 9 pivotally supporting a plate 10 of a length slightly less than the diameter of the flange 7 and movable into facial abutment with the side wall of the drum 6, as illustrated in full lines shown 70 in Fig. 1 or movable outwardly to the dotted line position indicated in Fig. 1 in which position the plate may be utilized to rotate the drum within the casing. The terminal of the pivoted plate carries a rotatably 75 mounted handle or knob 11 which, when the plate 10 is swung to closed or inoperative position is received within a radially elongated aperture 12 formed in the side wall of the drum 6. The terminal of the knob 11 is 80 enlarged and of substantially semi-spherical form providing a convex external surface for co-operation with the retaining and projecting spring to be hereinafter more fully described.

85 One angular terminal 13 of a spring wire 14 is soldered or otherwise rigidly secured at 15 internally of the drum 6 at a point adjacent the knob 11 when the latter is in closed or inoperative position and the body portion of the spring wire extends across the opening 12 and is adapted to be engaged and flexed by the semi-spherical terminal of the knob 11, during closing movement of the handle plate 10.

90 The opposite angular terminal 16 of the spring is rigidly connected with the flanged inner terminal 17 of a push button 18 slidably mounted in an aperture formed in the side wall of the drum 6 at a point adjacent 100 the knob carrying terminal of the plate 10 and adapted to be moved inwardly with relation to the drum to flex the body portion of the spring 14 and cause the latter to slide upon the convex external surface of 105 the knob. The inherent resiliency of the spring member 14 normally maintains the button 18 in outwardly projected position and a supplementary spring 19 of angular form is secured at one terminal to the button 110

18 and is soldered or otherwise rigidly secured at its opposite end as indicated at 20 to the circular flange of the drum 6 and assists in maintaining the button in outwardly projected position.

In its normal position, the medial portion of the spring 14 is so disposed as to be flexed inwardly incident to the inward movement of the knob 11 of the pivoted handle and 10 permits the most prominent portion of the spherical terminal of the knob to move inwardly past the axis of the spring and thus the latter exerting pressure against the convex surface of the knob maintains the latter 15 together with the plate 10 in inwardly disposed or inoperative position. However, in order to effect automatic projection of the knob from the drum it is simply necessary to depress the handle 18 thus flexing the 20 spring 14 causing the medial portion of the latter to move inwardly over the prominent portion of the spherical terminal of the knob 11 and operating against the curved surface of the latter projects the knob outwardly of the drum swinging the handle 25 plate 10 to the dotted line position in Fig. 1 and so disposing the knob as to provide a handle for convenience in rotating the drum with relation to the casing 5 and winding 30 the tape line thereon.

What I claim is:

1. The combination with the winding drum and pivoted handle of a tape line reel, said handle including a knob having an enlarged terminal, a U-shaped spring coacting with said enlarged terminal of the knob, one end of said spring being soldered to the flange of said drum and its opposite end to a push button, an auxiliary U-shaped spring 35 having one end thereof also soldered to the flange of the drum, rearwardly of the said terminal and its opposite end soldered to said push button to assist the first mentioned U-shaped spring in releasing the knob when 40 pressure is applied to the push button.
2. In a device of the character described, a tape case, a tape drum in said case having one end provided with an eccentric opening, a crank hinged to the end and provided with 45 a handle adapted to pass through said eccentric opening when closed, a device movable through the end of the drum, and a spring 50 actuated by the handle when the crank is closed to tension said spring for frictionally locking the handle and operated by the device to cause the spring to ride over the 55 handle and thereby automatically eject the latter from the opening, and a displaceable support for the last named means.

handle and thereby automatically eject the latter from the opening.

3. In a device of the character described, a drum, a crank pivoted thereto and having a handle projected into the drum when the crank has been closed, means within the drum in the path of movement of the handle to frictionally engage the latter and become tensioned thereby for holding the handle in the drum, and means exposed from the drum and operative upon the first named means to cause the same to ride upon the handle for the automatic ejecting thereof from the drum.

4. In a device of the character described, a tape case, a tape drum in said case having one end provided with an eccentric opening, a crank hinged to the end and provided with a handle adapted to pass through said eccentric opening when closed, a device movable through the end of the drum, and a spring actuated by the handle when the crank is closed to tension said spring for frictionally locking the handle and operated by the device to cause the spring to ride over the handle and thereby automatically eject the latter from the opening, and a displaceable support for the last named means.

5. In a device of the character described, a tape case, a tape drum in said case having one end provided with an eccentric opening, a crank hinged to the end and provided with a handle adapted to pass through said eccentric opening when closed, a device movable through the end of the drum, and a spring actuated by the handle when the crank is closed to tension said spring for frictionally locking the handle and operated by the device to cause the spring to ride over the handle and thereby automatically eject the latter from the opening, and a displaceable support for the last named means, the handle being formed with a bulged terminal for engaging the spring.

6. In a device of the character described, a drum, a handle movable into and out of the same, means within the drum to frictionally ride upon the handle for locking it within and ejecting the same from the drum, and a device actuated from without the drum for operating said means to move the same upon the handle.

In testimony whereof, I affix my signature hereto.

CHARLES W. CROGAN.
